UNITED STATES PATENT OFFICE.

WILLIAM MANNING, OF CHELMSFORD, MASSACHUSETTS.

IMPROVEMENT IN CORN-CAKE MACHINES.

Specification forming part of Letters Patent No. **56,241**, dated July 10, 1866.

To all whom it may concern:

Be it known that I, WILLIAM MANNING, of Chelmsford, in the county of Middlesex and State of Massachusetts, have invented new and useful Improvements in a Machine for Indenting and Finishing Corn-Cakes; and I do hereby declare that the following is a full and exact description thereof, reference being had to the accompanying drawings and letters of reference marked thereon.

The nature of my invention consists in providing a former to receive the parched, pulverized, prepared corn, to be operated on the table with any number of knives, for the purpose of indenting and finishing the corn-sheet in any number of squares, as required.

To enable others skilled in the art to make and use my invention, I will proceed to describe its construction and operation.

Figure 1 represents a plan of my improved machine for indenting and finishing corn-cakes. Fig. 2 represents a side elevation of the same. Fig. 3 represents a section through A and B of Fig. 1. Fig. 4 represents a plan of the former with a finished corn-cake, as required.

a represents the table; *b*, the stock; *c*, the knives; *d*, the springs; *e*, the self-adjusting clearers or hoofs; *f f*, the slides; *g g*, the guides; *h*, the joint; *i*, the lever; *j j*, the stoppin; *k k*, the former-guides; *l*, the former, and *m* the finished corn-cake.

The former *l* being filled with prepared corn and swept off even with the top of the sides,

it is then placed on the table *a*, adjusted in position by the guides *k k*, and moved back to the pins *j j*. Then the operator presses down the lever *i*, which operates on the joint *h* and depresses the slides *f* and stock *b*, the guides *g* keeping them in their vertical position, carrying down the knives *c* and the self-adjusting clearers or hoofs *e*, the hoofs *e* coming in contact with the corn-cake *m* first receiving the pressure from the springs *d*. The knives *c* are inserted sufficiently for the required indenture, then removed by the action of the lever *i*. The hoofs *e* serve to keep the edges of the indentures perfect and unbroken. Then the former *l* is removed from the table *a* and turned one-quarter around, and then placed back on the table *a* to the pins *j j*. By the same operation of the operator the indentures are made at right angles with the former ones. The cake is then finished and ready to be removed.

What I claim as my invention, and desire to secure by Letters Patent, is—

1. The stationary knives *c* and adjustable clearers or hoofs *e*, as herein described, and for the purpose set forth.

2. The former *l*, in combination with the adjustable clearers or hoofs *e* and knives *c*, for the purpose specified and in the manner set forth.

WILLIAM MANNING.
